[57] **CLAIM**

The ornamental design for a feeder for dogs, as shown and described.

DESCRIPTION

FIG. 1 is a top plan view of a feeder for dogs showing our new design;
 FIG. 2 is a bottom plan view thereof;
 FIG. 3 is a front elevational view thereof;
 FIG. 4 is a rear elevational view thereof;
 FIG. 5 is a right side elevational view thereof; and,
 FIG. 6 is a left side elevational view thereof.
 The broken lines in FIG. 1 are for purposes of illustration only and form no part of the claimed design.
